US0D1012285S

(12) **United States Design Patent** (10) Patent No.: **US D1,012,285 S**
 Timmins et al. (45) Date of Patent: ** Jan. 23, 2024

(54) **TWO-POINT DISCRIMINATION DEVICE FOR A LANYARD**

(71) Applicant: **OREGON HEALTH & SCIENCE UNIVERSITY**, Portland, OR (US)

(72) Inventors: **Benjamin H. Timmins**, Portland, OR (US); **Angelo B. Lipira**, Portland, OR (US); **Nichole Joslyn**, Portland, OR (US)

(73) Assignee: **Oregon Health & Science University**, Portland, OR (US)

(**) Term: **15 Years**

(21) Appl. No.: **29/736,899**

(22) Filed: **Jun. 3, 2020**

(51) LOC (14) Cl. **14-02**

(52) U.S. Cl.

USPC **D24/140**

(58) **Field of Classification Search**

USPC D24/133, 140, 142, 143, 147, 200, 214; D28/91.2, 99; D32/42-43, 46; D10/64, D10/70, 71, 72, 74

(57) **CLAIM**

The ornamental design for a two-point discrimination device for a lanyard, as shown and described.

DESCRIPTION

FIG. 1 is a front isometric view of a two-point discrimination device for a lanyard showing our new design.

FIG. 2 is a rear isometric view thereof.

FIG. 3 is a front elevation view thereof.

FIG. 4 is a rear elevation view thereof.

FIG. 5 is a right side elevation view thereof, of which the left side elevation view is a mirror image.

FIG. 6 is a top plan view thereof; and,

FIG. 7 is a bottom plan view thereof.

The broken lines in FIGS. 1-4 illustrate portions of the two-point discrimination device for a lanyard that form no part of the claimed design.

1 Claim, 3 Drawing Sheets
